UNITED STATES PATENT OFFICE.

MAURICE JEANTET, OF ST. CLAUDE, FRANCE.

TOBACCO-PIPE.

No. 877,777.

Specification of Letters Patent.

Patented Jan. 28, 1908.

Application filed March 29, 1907 Serial No. 365,269.

To all whom it may concern:

Be it known that I, MAURICE JEANTET, civil engineer, citizen of France, residing at St. Claude, Jura, in the Republic of France, have invented new and useful Improvements in Tobacco-Pipes, of which the following is a specification.

This invention relates to improvements in tobacco pipes and consists in novel means for destroying or reducing nicotin and acrid properties of tobacco smoke.

Numerous forms of tobacco pipes have been proposed for obviating or reducing the well-known disadvantages of nicotin, but being complicated or ineffective these forms have been found unsuitable.

By the present invention the improved tobacco pipe has the property, either by the composition of a suitable part located in it or by the composition of its whole, of insuring the destruction of the nicotin and acrid properties of the tobacco smoke, the said pipe being clearly distinguished from previous ones by certain characteristics which will hereinafter be described.

The annexed drawing represents by way of example a form of construction of the improved pipe.

In the interior of the bowl *a* of the pipe, which is of any usual material such as wood, meerschaum, asbestos, pipe clay or the like, is fixed a cylindrical jacket or lining *b* of retort-charcoal previously treated with a catalytic agent by being immersed for instance in a solution of platinum chlorid and then exposed to the reducing flame. During the smoking of the pipe a high temperature is produced in the bowl, and this enables the catalytic agent with which the porous jacket *b* is impregnated to produce by contact with the smoke small quantities of formyl which neutralize the nicotin and acrid properties of the tobacco. In manufacturing the circular jacket *j* one may also directly introduce

reduced metals into the paste serving to produce the charcoal.

The special internal lining of the pipe may have the shape of the bowl itself instead of being simply cylindrical, or the entire pipe may be constructed of a substance impregnated with catalytic agents.

It is obvious that the nature of the substance serving as support for the catalytic agents may be varied and also these agents themselves. Porous substances impregnated with reduced metals are preferably employed; for example retort charcoal, coke, graphite, asbestos, and even stone-ware, if once impregnated with catalytic agents, fulfil the purpose indicated. With regard to the catalytic agent, good results are obtained from perchlorid of platinum, and salts of copper, nickel, palladium and iridium when reduced.

Having now described my invention, what I claim as new and desire to secure by Letters Patent is:

1. A tobacco pipe comprising an ordinary pipe and a lining within the bowl of the pipe formed of a porous substance previously impregnated with a catalytic agent and subjected to a reducing flame, substantially as described and for the purpose set forth.

2. A tobacco pipe comprising an ordinary pipe and an internal lining within the bowl formed of retort charcoal previously immersed in a solution of chlorid of platinum and subjected to a reducing flame, substantially as described and for the purpose set forth.

In testimony whereof I have signed my name to this specification in the presence of two subscribing witnesses.

MAURICE JEANTET.
